UNITED STATES PATENT OFFICE.

HENRY FRANZ, OF PITTSBURG, PENNSYLVANIA, ASSIGNOR TO THE WINDSOR
GLASS COMPANY, OF SAME PLACE.

DESIGN FOR A TOOTH-PICK HOLDER, &c.

SPECIFICATION forming part of Design No. 17,345, dated May 17, 1887.

Application filed February 26, 1887. Serial No. 229,047. Term of patent 3½ years.

To all whom it may concern:

Be it known that I, HENRY FRANZ, a citizen of the United States, residing at Pittsburg, Pennsylvania, have invented and produced a new and original Design for a Tooth-Pick or Match Holder, of which the following is a full, clear, and exact description, reference being had to the accompanying drawings, forming a part of this specification, in which—
10 Figure 1 is a top view; Fig. 2, a sectional view on line X X of Fig. 1, and Fig. 3 a front elevation showing a suitable pattern or configuration upon its surface.

15 My invention has relation to a novel form of tooth-pick or match holder; and it consists in a hollow vessel exteriorly formed in the shape of a blacksmith's anvil. The outer surface of the vessel is ornamented by a series of

diamond-shaped projections, which so unite (when any six are taken together) as to form 20 a complete six-pointed star.

Having described my design, I claim—

The novel design for a tooth-pick or match holder, which consists in a hollow vessel exteriorly formed in the shape of a blacksmith's 25 anvil, the outer surface being ornamented by a series of diamond-shaped projections which so unite as to form a six-pointed star, substantially as shown and described.

In testimony whereof I have hereunto set 30 my hand this 21st day of February, A. D. 1887.

HENRY FRANZ.
